YARN WINDING MACHINE

Henry R. Childs, Kingsport, Tenn., assignor to
Eastman Kodak Company, Rochester, N. Y., a
corporation of New Jersey

Application October 31, 1940, Serial No. 363,620

9 Claims. (Cl. 242—18)

The present invention relates to yarn winding machines, and more particularly to an improvement in the guides over which the yarn passes on its way to the winding cone.

One object of the invention is the provision in an apparatus of this class of yarn guides which are so shaped as to reduce to a minimum the area thereof engaged by the yarn during its movement through the apparatus.

A further object of the invention is the provision of yarn guides which are in the form of curved surfaces of small radii to provide substantially point supports for the moving yarn.

A still further object of the invention is the provision of yarn guides which maintain a substantially constant ratio of yarn tension on opposite sides of the guides irrespective of the type of yarn passing thereover.

Still another object of the invention is the provision of small radius guides which provide a more positive control of the yarn tension during the winding of the cone, decrease the difference of yarn tension when changing from a full to an empty supply bobbin, and also facilitate the building of straight, ringless cones even when bobbins are changed before the cone is finished.

Yet another object of the invention is the provision of yarn guides of the class described which are simple in construction, inexpensive to manufacture, can be readily applied to existing machines, and which are highly effective in use.

To these and other ends, the invention resides in certain improvements and combinations of parts, all as will be hereinafter more fully described, the novel features being pointed out in the claims at the end of the specification.

In the drawing:

Fig. 1 is a side elevation view of a portion of a yarn winding machine, showing the relation thereto of yarn guides constructed in accordance with the present invention;

Fig. 2 is a fragmentary view of a portion of the mechanism illustrated in Fig. 1, but on a larger scale than the latter, with parts in section and parts in elevation, showing the arrangement of the traverse guide assembly with the yarn guides constructed in accordance with the present invention;

Fig. 3 is a front elevation view of the traverse guide assembly illustrated in Fig. 2, showing the arrangement in relation to the various yarn guides; and

Fig. 4 is a view similar to Fig. 2 showing the arrangement of the yarn guides on the traverse

guide assembly in use prior to the present invention.

Similar reference numerals throughout the various views indicate the same parts.

The coning machine most commonly used for winding synthetic filament yarn on to cones consists of a rotating spindle upon which the paper tube turns, a reciprocating guide which moves the yarn back and forth along the surface or periphery of the cone, various guides, tension devices, stop motion, etc. A typical example of this type of machine is shown in Figs. 1 and 4, in which the cone of yarn 11 is wound onto a paper tube 12 which is revolved in a clockwise direction by a spindle 13 on which the tube is supported. In prior arrangements, the yarn is guided onto the cone by a reciprocating button guide 14, of the type best shown in Fig. 4, which is connected by means of a traverse arm 15 to a cam, not shown. The traverse arm 15 is mounted in a slot in the traverse back 16 which is pivoted at 17 below the button guide in such a manner that it may move back as the cone builds up, allowing the curved front face 18 of the button guide 14 to be continuously but lightly pressed against the surface of the cone, as is well known. The yarn 19 is pulled from a bobbin 20 through a tension gate 21, through a slab catcher 22, underneath the stop lever 23, over a curved surface guide of large radius 24, known as a slide arm, to the button guide 14.

It will be noted from Fig. 1 that the yarn 19 is pulled vertically upward from the bobbin 20 and then after passing over the various guides at various angles until, at the point where it is wound onto the cone 11, it is traveling vertically downward, thus having changed its course 180 degrees.

In the prior constructions, button guide 14 has had a V-shaped slot 26 formed therein, the base 27 of the slot being shaped on an arc of a circle of relatively large radius, as clearly illustrated in Fig. 4. From this figure it will be readily apparent that the yarn contacts the base 27 of the guide 14 throughout its entire length. The slide arm 24 of prior devices is fixed to the traverse back 16 and does not reciprocate with the button guide 14. The yarn 19 passes over the curved surface 25 of the arm 24 while playing back and forth along its length with the motion of the button guide. This reciprocating motion along the surface of the slide arm imparts both a shearing and tensile stress to the yarn at that point. The button guide is made of any suitable material, such as porcelain, or case hardened polished

metal. The surface 25 of the arm 24, as well as the slot 26, of the button guide 14, are highly polished so as to reduce the friction of the moving yarn thereover. Thus the yarn, under the tension applied at the tension device or gate 21, passes over the polished curved surfaces 25 and 27, the radii of which are made relatively long to prevent undue wear from contact with the yarn.

In coning ordinary yarn, no difficulty has been encountered which might be attributed to the yarn guides. Synthetic yarns are usually given three to five twists or turns per inch before the coning operation. However, there has arisen recently a demand for yarns having a lower twist; for example, one and a quarter turns per inch or less. This material is used for various purposes where the amount of twist used is not important in order to effect an economy in the production of the yarn. For example, for certain purposes, yarns containing very low twists (one-quarter to one-half turns per inch) may be used. This type of material would be suitable for plying with synthetic or natural fiber of a different type where additional twist would be inserted in the plying operation.

It has been found, however, that yarns containing low twists (less than two turns an inch) are difficult to cone on the commonly used type of machine, as described above. There is a tendency for some of the filaments to become separated from the main body of the strand, causing loops or broken filaments. These defects are carried on into the finished fabric causing inferior quality. In an effort to improve this condition many things have been attempted; as for example, various changes in the lubricating treatment of the yarn, but none of these efforts have been successful.

In practice it is customary to apply a given amount of tension to the yarn by loading or weighting the tension device. The amount of tension applied varies with the denier, the hardness of the cone desired, and various other well-known factors. A convenient means of measuring and controlling the tension is to insert a tensiometer between the tension gate 21 and the button guide 14. It is desirable that the tension should be relatively high at the start of the cone, gradually decreased as the cone builds up in order to compensate for the increasing speed. The tension that is measured before the button guide is not, however, the actual tension that exists at the point of winding or of application of the yarn to the cone 11. The tension at that point may be measured by taking the end of the yarn vertically downward from the button guide 14, over a pulley or guide, not shown, and back up to the opposite side of the cone. A tensiometer, not shown, may now be inserted directly below the button guide, and this meter will then indicate the tension that would ordinarily exist at the point of application of the yarn on the cone.

This method has been used to determine the increased tension encountered with various types of yarn passing over the traverse guide assembly which constitutes the button guide 14 and the guide 24. The tension gate 21 was set to give various predetermined tensioning values ahead of the button guide 14, and the corresponding tensions beyond the button guide were then noted. These ratios of tensioning after and before the button guide might be called the coefficient of friction of the yarn passing over the button guide assembly. As a result of the test,

it was found that this coefficient of friction varies widely with the type of yarn. Very surprisingly, this variation seemed to be a function of twists in the yarn. That is, the lower the twists, the higher the coefficient of friction encountered in passing over the button guide assembly.

It was noted that yarns having three turns per inch or more, the coefficient of friction was about 2.0, varying slightly above or below with luster. The coefficients of friction of low twist yarns were, however, considerably higher, reaching in some instances to 5.0. It so happens that the yarn types having the greatest coefficient of friction, low twist yarns, have given the most difficulty in the coning operation. It is logical to assume, therefore, that the damage done to this low twist yarn in winding occurs at the button guide. Furthermore, any change in the shape of the button guide which would lessen the coefficient of friction for low twist yarn would improve the quality of the yarn in winding.

It was found that it was only necessary to change the shape of the curved surfaces of the traverse guide assembly, see Fig. 2, so that the arcs of contact with the yarn are reduced to a substantially small radii to accomplish this purpose. This change is clearly illustrated in Figs. 2 and 3. To secure this result, the bottom of the slot 26 of the button guide 14 was hollowed out to provide a sloping or inclined bottom 35, the apex 36 of which is positioned adjacent the curved face 18 of the button guide 14, as clearly illustrated in Fig. 2. This apex is also in the form of a short curved surface of small radius 35 over which the yarn 19 passes and which affords a substantially point support for the yarn adjacent the cone 11, as will be later more fully explained. The traverse slide arm 24 has also been removed and replaced by a guide member, broadly designated by the numeral 37 of the shape best shown in Figs. 2 and 3. This new guide member is formed of small round wire, such as steel music wire, which may be surface hardened or plated, and has the ends 38 thereof secured to the traverse arm 15 by screws 39 or other suitable fastening means.

By means of this arrangement, the guide 37 will move as a unit with the button guide 14 during the yarn winding operation, thus eliminating the necessity of the yarn sliding along the length of the guide as in prior constructions. The intermediate portion of the guide member 37 is formed with a U-shaped portion or throat 40 the bottom or base 41 of which is positioned in lateral alignment with the inclined bottom 35 of the new button guide 14, as clearly shown in Fig. 3. The yarn 19 in moving from the tension gate 21 to the button guide 14 passes over and is supported by the bottom 41 of the guide member 37. As the latter is formed from wire of small radius, the yarn will engage the bottom 41 over only a relatively small area so that the bottom may be broadly considered as providing substantially a point support for the yarn as the latter passes over the guide member 37. Furthermore, the bottom 41 is rounded, as best shown in Fig. 3, so that the yarn may play back and forth across a small section of the bottom to thus prevent excessive wear.

This guide member 37 may be readily replaced in case of wear or breakage, as is apparent. The precise shape and location of the guide 37 are not critical so long as the guide forms substantially a point support for the yarn as it passes over this guide member, and also serves to guide

the yarn toward the button guide 14 in such a direction that the yarn will engage the curved apex 36 in a direction substantially tangential thereto, as clearly shown in Fig. 2. By thus directing the yarn towards the button guide, the yarn engages the latter only at a point which is tangent to the curve of the apex 36, thus providing a point contact or support for the yarn adjacent the face 18, or the point of application of the yarn to the cone 11, as will be readily apparent from an inspection of Fig. 2.

By means of these point supports, the coefficient of friction of the assembly, as shown in Fig. 2, is much less than for the long radius guides previously used and shown in Fig. 4. Furthermore, the coefficient of friction of this new arrangement is almost independent of the yarn twists, being relatively uniform for all types of yarn. In addition, the tension increase passing over such small radius guides is less than even the normal increase for the traditional type of long radius guides of prior machines as illustrated in Fig. 4. The reason for this yarn behavior is not readily explainable, but it is reasonable to believe that the filaments of low twist yarn tend to separate in passing over the relatively long areas of contact commonly used in coning machines of the class illustrated in Fig. 4. The filaments that become separated from the strand tend to increase the friction by increasing the effective area of contact. The friction thus created tends to tear the isolated filaments and group them into loops. Since the increased friction is not encountered with short radius guides of the present invention, a great improvement should be expected in the quality of the low twist yarn wound with them. This anticipated improvement has been verified under actual operating conditions, and the percentage of defective cones has been very materially reduced.

In addition to this remarkable improvement in quality which has been obtained by the use of these new small radius guides, there is another distinct advantage to be realized in the use of such an arrangement; namely, the control of tension. As mentioned above, it is desirable to start with a relatively high tension which gradually decreases with the increase of the cone diameter, or winding speed. This condition is necessary in order to build a cone having straight ends which are vertical to the axis of the cone. In practice, however, it is not always possible to maintain this condition. The tension must be derived from two sources: (1) the gate tension device 21 which is controllable according to any predetermined setting with respect to the size of the cone, and (2) the friction encountered in ballooning around the head of the bobbin 20. The latter increases with the speed of withdrawal, and cannot be controlled. It happens, therefore, that it is not possible to obtain a uniform reduction in tension when coning low twist yarn over long radius guides of the type shown in Fig. 4. The high coefficient of friction, as mentioned above, makes it necessary to remove all tension from the gate 21 while the cone is still small to prevent the final tension from becoming too high. As a result of tests, it was found that there is a sharp change in the tension at the point where the cone has reached a depth of about one-half inch. At that point, even with the gate tension fully open, the tension starts to increase due solely to the withdrawal tension. Beyond that point it is not possible to control the tension without making it even greater than it is.

Furthermore, it has also been found that the tension is higher for a bobbin containing a small amount of yarn, and this difference is greatly magnified in passing over the button guide assembly. Since it is often necessary to change from an empty to a full bobbin before the cone is completed, there is a sudden shift in tension in the yarn. This sudden change invariably produces an unsightly ring at the point where the bobbin was changed, the disadvantages of which will be apparent to those in the art.

With the small guides of the present invention, it is possible to control the tension throughout the entire winding of the cone. The increased tension at the traverse guides is only about one-half as great as with prior arrangements, and it is not necessary to relieve the tension at the tension gate 21 before the cone is finished. Although the initial tension is greater with the present form of guides, the final or effective tension is less, and this tension uniformly decreases as the cone fills up. Furthermore, the difference in tension from a full to an empty cone is much less. These conditions facilitate the building of straight ringless cones even when bobbins are changed before the cone is finished.

While the above described improvements are particularly desirable and noticeable with low twist yarns, the application of small radius guides are not limited thereto. While the coning of high twist yarn has always been satisfactory with prior guides, as shown in Fig. 4, considerable improvement in the quality of high twist yarns was also secured when small radius guides are used in connection with the coning thereof.

It is thus apparent that the use of the small radius guides of the present invention provides point supports for the yarn as it passes over the various guide members to thus materially reduce the friction of the yarn thereon. These guides also maintain a substantially constant ratio of yarn tension on opposite sides of the button guide, and provide a more positive control for the yarn tension during the winding operation, and finally, facilitate the building of straight, ringless cones which are highly desirable.

While one embodiment of the invention has been disclosed, it is to be understood that the invention idea may be carried out in a number of ways. This application is therefore not to be limited to the precise details described, but is intended to cover all variations and modifications thereof falling within the scope of the appended claims.

What I claim is:

1. In a yarn winding apparatus, the combination with a rotating winding cone on which may be wound in successive convolutions, of a traverse guide assembly mounted to reciprocate longitudinally of said cone to guide said yarn thereon, and a curved surface of small radius formed on said assembly to provide a substantially point support for said yarn adjacent the point of application of said yarn on said cone.

2. In a yarn winding apparatus, the combination with a rotating winding cone on which yarn may be wound in successive convolutions, of a traverse guide assembly mounted to reciprocate longitudinally of said cone to guide said yarn thereon, a curved surface of small radius formed on said assembly adjacent said cone, and a guide carried by said apparatus for directing said yarn toward said surface in a direction tangentially thereof so that said surface will provide a sub-

stantially point support for said yarn adjacent said cone.

3. In a yarn winding apparatus, the combination with a rotating winding cone on which yarn may be wound in successive convolutions, of a traverse guide assembly comprising a button guide mounted to reciprocate longitudinally of said cone to guide the yarn thereon, a curved surface of small radius formed on said button adjacent the point of application of said yarn to said cone, and a guide carried by said apparatus and positioned above said surface to direct said yarn toward said surface in a direction tangential thereto so as to engage the latter substantially only at a single point.

4. In a yarn winding apparatus, the combination with a rotating winding cone on which yarn may be wound in successive convolutions, of a traverse guide assembly comprising a button guide mounted to reciprocate longitudinally of said cone to guide the yarn thereon and having a portion thereof adapted to press lightly against the yarn on said cone, a curved surface of small radius formed on said button guide adjacent said portion to afford a point support for said yarn on said button guide, and means carried by said apparatus and positioned relative to said button guide to guide said yarn thereto in such a manner as to engage said button guide only at said point.

5. In a yarn winding apparatus, the combination with a rotating winding cone on which yarn may be wound in successive convolutions, of a traverse guide assembly comprising a button guide mounted to reciprocate longitudinally of said cone to guide the yarn thereon, said button guide being provided with a slot the base of which is formed with a curved surface of small radius positioned at the discharge end of said slot, and guide means carried by said apparatus for directing said yarn into said slot in a direction tangential to said surface so that the latter will provide a substantial point support for the yarn at the point of application thereof to the cone.

6. In a yarn winding apparatus, the combination with a rotatating winding cone on which yarn may be wound in successive convolutions, of a traverse guide assembly comprising a button guide mounted to reciprocate longitudinally of said cone to guide the yarn thereon, a curved surface of small radius formed on said button adjacent the point of application of said yarn to said cone, a yarn guide member positioned in advance of said button guide to direct said yarn thereto, and an arcuate yarn guiding portion on said member arranged in alignment therewith and positioned relative thereto to direct said yarn to said button guide so as to engage said surface only at a point, said portion being of small radius to afford a substantially point support for said yarn as it passes thereover.

7. In a yarn winding apparatus, the combina-

tion with a rotating winding cone on which yarn may be wound in successive convolutions, of a traverse guide assembly comprising a button guide mounted to reciprocate longitudinally of said cone to guide the yarn thereon, a curved surface of small radius formed on said button adjacent the point of application of said yarn to said cone, a guide member operatively connected to and movable as a unit with said button guide along said cone, and a small radius yarn guiding portion on said member arranged in alignment with said surface and positioned vertically relative thereto to direct said yarn toward said surface to engage the latter only at a point.

8. In a yarn winding apparatus, the combination with a rotating winding cone on which yarn may be wound in successive convolutions, of a traverse guide assembly comprising a button guide mounted to reciprocate longitudinally of said cone to guide the yarn thereon, said button guide being provided with a slot formed with an inclined bottom, a curved surface of small radius formed on said bottom adjacent said cone, a guide member operatively connected to and movable as a unit with said button guide along said cone, an intermediate yarn guiding portion on said guide member, and a curved yarn supporting section formed on said intermediate portion and positioned in alignment with and slightly above said surface to direct said yarn toward and in a direction tangentially of said surface so that the latter will provide a point support for said yarn adjacent said cone, said curved section being of small radius to provide substantially a point support for said yarn as it passes over said guide member.

9. In a yarn winding apparatus, the combination with a rotating winding cone on which yarn may be wound in successive convolutions, of a traverse guide assembly comprising a button guide having a face adapted to lightly engage the periphery of said cone, a button guide holder mounted for reciprocating movement on said apparatus to move said button guide longitudinally along said cone to feed the yarn thereonto, said button guide being formed with a slot the apex of which is positioned adjacent said face, a curved surface of small radius formed at said apex, a yarn guide member positioned in advance of said button guide and secured to said holder so as to move across said cone as a unit with said button guide, and a small radius yarn guiding and supporting portion formed on said guide member and arranged in lateral alignment with said slot, said portion affording substantially a point support for said yarn and being positioned slightly above said surface so as to direct said yarn in a direction tangentially of said surface so as to contact the latter at a point only adjacent said cone.

HENRY R. CHILDS.
